UNITED STATES PATENT OFFICE.

HENRY K. STEVENS AND SOLOMON MILLER, OF WATERLOO, NEW YORK;
SAID MILLER ASSIGNOR TO SAID STEVENS.

IMPROVEMENT IN SCREW-PROPELLERS.

Specification forming part of Letters Patent No. 142,820, dated September 16, 1873; application filed
March 13, 1873.

To all whom it may concern:

Be it known that we, HENRY K. STEVENS and SOLOMON MILLER, of Waterloo, Seneca county, New York, have invented certain Improvements in Propeller for Steam - Vessels, which we denominate the "Hercules Propeller," of which the following is a specification:

The first part of our invention consists in the construction of the blades of the propeller, by which, with a greater number of blades than is now used we have a larger and freer water - space for the passage of the water through the wheel than any propeller heretofore constructed with which we are acquainted, thereby furnishing a larger amount of water for the propelling surfaces to act upon, by which the slip is decreased when the wheel is in rapid motion.

The second part of our invention is the coupling for uniting the driving-shaft with the propeller.

The construction of the propeller is as follows, referring to the accompanying drawing, in which—

Figure 1 is a general view of the propeller. Fig. 2 is a side elevation. Fig. 3, the coupling joint.

The hub *a* is of ordinary form tapered at each end. The blades *b* are six in number, and are joined to the hub at an angle of about thirty-five degrees to the shaft. The center line of the blade *b* is curved backward. It starts at an angle from a radial line at that point, curving upward at right angles to the line of the base, inclined backward to the center of the length of the blade; and thence curving forward to the outer periphery of the blade, as clearly seen in the drawing. The rear edge of the blade has a nearly similar curve, rounding off at the periphery. The front edge of the blade curves much more, extending forward of a radial line, and expanding out the outer circumference of the blade to about double the breadth at the hub, and terminating forward in a rounded point, as clearly illustrated in Fig. 1. Both faces of the blade are convex in their cross-section, tapering to an edge in front and rear, the thickness also diminishing from the hub to the tip.

The form we thus give to our propeller-blades allows much greater space for water-

way than is had in the ordinary propeller, and enables us to increase the number of our blades to six, which gives our propeller a steadier motion, but would be fatal to the ordinary propellers heretofore made.

The action of our propeller is to gather and consolidate the water in the rear, thereby increasing force instead of dispersing it, and thereby breaking and churning it as the propellers now in use do, which is so fatal to rapid motion. This action of our propeller decreases the wash on the sides.

The axis of our propeller is hung in bearings in a stout metal rudder - frame, *c*, having fender - braces *d* projecting horizontally therefrom, which surround the propeller. This rudder - frame is pivoted to the stern-post of the boat, or to outriggers *e*, and is so connected with the tiller *f* above as to be readily swung to the right or left thereby.

The driving-shaft *h* of the engine projects out through the stern-post of the vessel, and is coupled with the axis of the propeller by a flexible coupling joint, constructed so as to give freedom of motion, and at the same time sufficient strength for the purpose. To effect this I form two jaws upon the shaft *h*, circular on their face *i*, as seen in the drawing. Similar jaws are affixed to the axis of the propeller, which couple into those on the shaft *h*. These jaws are united by joint-pins to hold them in place, the whole strain coming upon the jaws.

Having thus fully described our invention, what we claim, and desire to secure by Letters Patent, is—

1. The propeller constructed and arranged as herein described, having the blades formed and affixed to the hub, as herein specifically set forth in the above description, and for the purposes specified.
2. The joint herein described, for coupling the propeller, with the driving-shaft composed of strong jaws united together and held in place by pins, as herein described.

In testimony whereof we hereto set our hands.

HENRY K. STEVENS.
SOLOMON MILLER.

In presence of—

HUGH MONTGOMERY,
H. VAN AMBURGH.
